Elisha Town of Montpelier Vermont
Letters Patent.

The Schedule referred to in the Letters Patent and making part of the same contains a description in the words of the said Elisha Town himself of his improvement called "Young Rotary Stove".

To all persons to whom these presents shall come, Elisha Town of Montpelier in the County of Washington and State of Vermont. Gentlemen. And Greeting. I Do it know that I the said Elisha Town have invented constructed made and applied to use a new and useful improvement in Cooking Stoves, called "Young Rotary Stove", Specified in the words following to wit, This improvement in cooking Stoves consists. First of a fire room proportioned to the size of the Stove, and the fuel to be used therein, with an oven back of and upon a back with the dome above and below which over the heat and smoke passing toward the fire in the back plate of the stove. Second, in having a circular projection on each side of the plate which covers the oven and a part of the fire room, upon the upper side and at or near the edge of which plate there is a circular rim raised sufficiently high to permit a portion of the heat and smoke to pass over the oven to the fire and also to permit the boiling kettle and other cooking utensils, that may be put into the rotary plate to pass over the top of the oven. A large circular plate is placed over the fire room in such a manner that a segment of about one third of the diameter of the circular plate is occupied by the fire room. For the above described parts of the Stove I do not claim letters Patent, as I do not claim them as a part of my invention. Third, above the said circular rim and resting on the same is a circular rotary plate projecting a little beyond the said rim, which plate may be rotated by a central pivot projecting therefrom down through the bottom plate of the Stove for the convenience of raising the rotary plate from its bearing, a lever attached to and underneath the bottom plate of the stove, into the bottom plate of the stove are two perpendicular pieces of iron inserted connected together at the bottom between which the lever hangs, acting on a pin running through said pieces of iron as a fulcrum, on the short arm of which lever rests the before described pivot. The rotary plate is constructed with holes or notches placed therein for boiling kettle & other cooking utensils. The principle for which we claim the invention

tin and for which I would apply for a Patent of the United States is the combining
top piece or feature onto or on which are placed the principal utensils used
in cooking and for other purposes to which the stove may be applied.

I declare my that the above is a true specification of my said improvement as
above described. I have hereunto set my hand this twenty second day of April
in the year of our Lord one thousand eight hundred and thirty four.
